UNITED STATES PATENT OFFICE.

LOUIS W. PIETSCH, OF POST FALLS, IDAHO.

SMOKE-CONDUCTING PIPE.

1,131,159.

Specification of Letters Patent.

Patented Mar. 9, 1915.

Application filed June 16, 1913. Serial No. 773,954.

To all whom it may concern:

Be it known that I, LOUIS W. PIETSCH, a citizen of the United States, residing at Post Falls, in the county of Kootenai and State of Idaho, have invented new and useful Improvements in Smoke-Conducting Pipes, of which the following is a specification.

This invention relates to improvements in soot and other residue elimination devices for the smoke conducting pipes of furnaces leading from the latter to the stack and the invention is especially adapted for commercial furnaces where extraneous matter carried by the smoke is particularly troublesome.

The present invention is an improvement on the invention disclosed in my pending application filed the 25th day of March, 1913, but one of the objects of this invention is to reduce the smoke to a colorless vapor without offering any appreciable resistance to the draft thereby enabling the device of the invention to be effectively used with a natural draft and avoiding the necessity of a forced or induced draft appliance.

A further object is to provide drainage whereby the matter separated from the vapor may be continuously drawn off, this feature also including piping so arranged that interior portions can be cleaned and drained off through the main drainage piping.

Other features of novelty will be more fully described in connection with the accompanying drawings and will be more particularly pointed out in and by the appended claims.

In the drawings: Figure 1 is a view in side elevation of one form of my invention with parts broken away. Fig. 2 is a sectional view on line 2-2 of Fig. 1. Fig. 3 is a perspective view of the structure shown in Fig. 2. Fig. 4 is a detail view. Fig. 5 is a sectional view on line 5-5 of Fig. 3.

Like characters of reference designate like parts throughout the different figures of the drawings.

As shown, the device of my invention includes a smoke receiver 1, adapted for connection with the furnace, and a receiver 2, adapted to deliver to a stack, not shown, the said receivers being connected by piping for conveying the smoke in its passage from receiver 1 to 2. The receiver 1 may be provided with baffles 8 disposed in a manner to cause the smoke to take a tortuous course

through receiver 1 so as to arrest passage of the coarser particles by reason of their engagement with said baffles.

Leading from the receiver 1 is a plurality of pipe sections 4, 5 and 6 which may take the form of elbows and which are shown as being downwardly directed. These elbow sections are each provided with dampers indicated at 7, 8 and 9 so that any one of the same may be cut out of service for cleaning or repair purposes without affecting the others. The sections 4, 5 and 6 deliver to pipe sections 10, 11 and 12 which are shown vertically disposed to convey the smoke downwardly and which are provided in superposed pairs for each piping. The lowermost of the sections 10^a, 11^a and 12^a deliver to trap sections 13, 14 and 15 and the latter discharge into the stack receiver 2.

A supply pipe 16 is provided with branch pipes 17 and 18 and the former has nozzle pipes 19 and 20 connected with sections 10 and 10^a of one piping, respectively, while the latter has nozzle pipes 21, 22 and 23, 24, of the sections 11, 11^a and 12, 12^a of the remaining piping, as will be clearly seen in and by reference to Fig. 1. A drain pipe 25, which may be connected with a sewer or other outlet, is provided with branches 26 and 27 leading upwardly, as shown. Branch 26, is provided with drainage connections 28 and 29, leading to sections 10 and 10^a, and said pipe or branch 26 is also provided with connections 30 and 31, leading to sections 11 and 11^a, respectively. Branch 27 is provided with connections 32 and 33, leading to sections 12 and 12^a, respectively. A trap drainage branch 34 extends upwardly from pipe 25 and has valved connections 35, 36 and 37 leading to the flushing trap portions 38, 39 and 40, of sections 13, 14 and 15, respectively. It will thus be seen that independent flushing or cleaning of any of the pipe sections can be carried out while the remaining sections are in service by suitable operation of the valved connections just described. Further, the bent or trapped portions 38, 39 and 40 serve to prevent the flushing water from passing into the receiver 2.

The sections 10 to 12^a are of identical construction and therefore only one need be described in detail and reference will now be made to Figs. 2 and 3. These sections are made of vitrified or other non-corrosive material and section 10 consists of a pipe

2
casing 41, having suitably flanged ends 42 and 43, as shown, for connection with the ends of adjacent sections. Said casing also has a seat 44 adapted to receive the flanged head 45, of a removable nozzle smoke conducting separating pipe 46 which extends downwardly in the casing 41 and which is reduced in diameter with respect thereto. A collecting cup 47 is disposed in said cas-

10 ing 41 and is arranged with its open end facing in the direction in which the smoke approaches and said open end is disposed in overlapping relation with the lower end of pipe 46 so as to cause the smoke to reverse 15 its path of travel through the casing in its passage from the pipe 46, through the cup 47, into the casing 41.

The cup 47 is removably mounted in the casing 41 and I have shown the cup provided with lugs 48 adapted to seat on lugs 49, projecting inwardly from the casing 41. The lower end or the bottom of the cup is provided with an outlet pipe 50 communicating with the drainage connection 28. 25 The nozzle pipe 19 extends through the casing 41 and into the pipe 46 and is provided with a nozzle 51, adapted to discharge steam or water into pipe 46 to separate soot and other particles of matter from the products 30 of combustion and render the same a colorless vapor as nearly as possible. The particles of matter damped by the steam or water will be weighted, as it were, and they will descend into the collecting cup while 35 the vapor will take the course indicated by the arrows in Fig. 2. There will be sufficient liquid, even with the condensation of steam, to carry the separated particles deposited in the cup out through the drainage connections hereinbefore described. 40 Thus it will be seen that I not only do not cause any material resistance to the travel of the smoke, but by reason of the fact that I reduce its volume by separation therefrom 45 of soot particles there will be a freer passage of the vapor after it leaves the cup because of the reduced volume and weight and therefore any slight resistance to draft will thus be overcome and the device can be operated 50 under a natural draft.

In order to facilitate the cleaning of the outer wall of the cup and the inner wall of the casing so as to prevent restriction of passage at 52, due to collection of matter after 55 long usage, I provide an opening 53, in the casing 41, and on the margins of said opening are hook-like lugs 54 adapted to be engaged by projections 55, on a closure 56. The latter may be provided with a projecting 60 handle to permit of the closure being turned to lock or unlock the projections 55 with the lugs 54.

If it is desired to wash out or clean one pipe line, its damper 7, for instance, will be 65 turned to cut such pipe out of service and

the closures will be removed to give access to the cleanout openings 53 into which a hose may be inserted to flush or clean out the interior of the pipe line. The valved connection 35 will be opened to drain off the 70 water through pipe 34. The interior portions of the cups can be cleaned by flushing the same from the nozzles and draining off through the pipe 26.

I preferably use steam where sulfur is 75 present in the products of combustion and where it is desired to produce sulfuric acid.

While I have herein shown and described one embodiment of my invention I do not wish to be limited thereto except for such 80 limitations as the claims may import.

I claim:—

1. In a spark arrester, a smoke conducting pipe having an upright pipe section interposed therein provided with cup supporting lugs projecting interiorly thereof, a collecting cup of reduced cross section with respect to the interior cross section of said pipe section and provided with lugs adapted to seat on the lugs of said pipe section to 90 removably support the cup in spaced relation in and with respect to the interior of said pipe section, a separating pipe having a flange engaging said pipe section to removably support said separating pipe in 95 said pipe section and said separating pipe being of sufficient length to project downwardly into said cup, substantially as described.

2. In a spark arrester, a smoke conducting 100 pipe having an upright pipe section interposed therein and provided with cup supporting lugs projecting interiorly thereof, a collecting cup of reduced cross section with respect to the interior of said pipe section 105 and provided with lugs adapted to seat on the lugs of said pipe section to removably support the cup in spaced relation in and with respect to the interior of said pipe section, a separating pipe having a flange engaging said pipe section to partially close the same and to removably support said separating pipe in said pipe section, said separating pipe being of sufficient length to project downwardly into said cup, said cup 110 having a drainage pipe, and a drainage connection extending through said pipe section and connected with the drainage pipe of said cup, substantially as described.

3. In a spark arrester, a conducting pipe 115 having an upright pipe section interposed therein and including cup supporting means, a collecting cup removably supported in said pipe section on said means, the upper end of said section having an inner flange closure seat portion and outer annular pipe seat portion one being above the other, a separating pipe having a closure flange seated on said inner annular portion and said pipe being of sufficient length to depend 120 125 130

downwardly into said cup, said cup having a drainage pipe, and a drainage connection extending through said upright pipe section and coupled to said cup drainage pipe, substantially as described.

4. In a spark arrester, a smoke conducting pipe having an upright pipe section interposed therein for a downward passage of smoke thereto, a separating pipe of reduced 10 cross section with respect to the cross section of said pipe section and extending downwardly therein, a collecting cup disposed in said pipe section and having its upper open end disposed in surrounding relation and 15 above the lower end of said separating pipe

to cause the smoke flowing downwardly through separating pipe to flow upwardly over the open end of said cup and then downwardly outside of said cup in said pipe section, a nozzle for projecting a stream 20 into said separating pipe at substantially right angles to the longitudinal axis thereof, and a drainage pipe leading from said cup, substantially as described.

In witness whereof I hereunto affix my 25 signature in the presence of two witnesses.

LOUIS W. PIETSCH.
